UNITED STATES PATENT OFFICE.

EUGENE DE KLEIST, ON NORTH TONAWANDA, NEW YORK.

AUTOMATIC MUSICAL INSTRUMENT.

SPECIFICATION forming part of Letters Patent No. 770,862, dated September 27, 1904.

Application filed February 6, 1903. Serial No. 142,198. (No model.)

To all whom it may concern:

Be it known that I, EUGENE DE KLEIST, a citizen of the United States, residing at North Tonawanda, in the county of Niagara and State 5 of New York, have invented new and useful Improvements in Automatic Musical Instruments, of which the following is a specification.

This invention relates generally to pneumatic actions for piano-players, automatic 10 pianos, and similar musical instruments, and more particularly to an action of the kind shown and described in an application for Letters Patent of the United States filed by me on the 21st day of January, 1902, Serial 15 No. 90,639.

The objects of my present invention are to facilitate the adjustment of the suction and vent valves of the pneumatic action, to render them prompt and sensitive in operation, 20 and to mount the same upon their stems in such a manner that they may freely accommodate themselves to any irregularities or imperfections of their seats.

In the accompanying drawings, consisting 25 of two sheets, Figure 1 is a fragmentary vertical section of a piano-player containing my improvements. Fig. 2 is a similar section in line 2 2, Fig. 1. Figs. 3 and 4 are horizontal sections in the correspondingly-numbered 30 lines in Fig. 1. Fig. 5 is an enlarged vertical longitudinal section of one of the valve-chambers and adjacent parts.

Similar letters of reference indicate corresponding parts throughout the several views.

A indicates the inclosing case of the piano-player; B, its keys or fingers which operate upon the piano-keys C C' and which in the construction shown consist of the upper arms of bell-crank levers B'.

D indicates the motor-pneumatics, the movable boards of which are connected with the lower arms of the bell-crank levers B' by rods d. These pneumatics are arranged in several rows and preferably in the usual stepped 45 order, as shown in Fig. 3.

E is the main wind or exhaust chest, arranged transversely in the front portion of the case, and e is the duct by which it is con-

nected with a suitable exhaust device. (Not shown in the drawings.)

Each of the motor-pneumatics D is connected with an independent valve-chamber or auxiliary exhaust-chest F by ducts g g', formed in wind-boards G G', a duct g², formed in the main wind-board E', and ports g³ g⁴, formed in the front and rear walls of the main wind-board, as shown in Fig. 1. These valve-chambers are preferably arranged horizontally and communicate with the main exhaust-chest E and the atmosphere by ports h h', formed in their front and rear ends, respectively. In the preferred construction shown in the drawings each valve-chamber is composed of two sections, which are applied to opposite sides of the main wind-board, so that the chamber is partly inside and partly outside of the exhaust-chest. The exhaust and vent ports h h' of each valve-chamber are controlled by valves i i', preferably arranged within the chamber so as to close against the inner sides of the 70 ports. The valves of each pair are mounted on stems j j', carried by a sliding connecting-rod k, which is preferably square or of other flat-sided form, and guided in corresponding openings formed in supporting-bars l, as 75 shown in Figs. 1, 2, and 5. These bars extend across the ports g³ g⁴ and in the construction shown in the drawings are secured in grooves formed in the front and rear sides of the main wind-board. The stem j' of the 80 vent-valve consists of a screw which engages in a longitudinal opening in the rear end of the valve-rod k, so that it can be screwed more or less into the same for varying the aggregate length of the valve rod or stem 85 and properly adjusting the vent and exhaust valves with reference to their seats. The adjustable stem j' extends through the vent-port h' and terminates in an eye j² or other suitable enlargement for conveniently turning it. The stem j of each exhaust-valve is suitably secured to the front end of the valve-rod k. It is preferably pointed at its rear end and driven into the said rod, as shown. In the preferred construction of the valves illustrated in the drawings the same are capable 95

of rocking or swiveling on their stems, so as to seat squarely against the end walls of the valve-chambers even if these walls should not be perfectly true or at right angles to the 5 valve-stems. For this purpose each valve is clamped upon its stem by nuts m m' , which bear against opposite sides of the usual leather or other flexible facing i^2 of the valve, but not against the button forming the rigid body 10 of the valve. This button is provided centrally with an opening i^3 , which receives the rear clamping-nut m and which is sufficiently larger than the nut to permit the valve to 15 swivel freely on its stem in accommodating itself to any imperfections of its seat. The clamping-nuts m m' , while holding the valve against longitudinal displacement on its stem in both directions, permit the valve to be conveniently adjusted lengthwise of the stem. In 20 order to promptly close the exhaust-valves and open the vent-valves, a spiral spring n is applied to the stem j of each exhaust-valve between the latter and the front guide-bar l of the valve-rod k . As this spring bears 25 evenly against the exhaust-valve on all sides of its stem, it insures a reliable closure of the valve.

The devices for opening and closing the exhaust and vent valves form no part of my invention and may be of any suitable or well-known construction. Those shown in the 30 drawings consist of the usual tracker-board o , over which the perforated music-sheet travels, and diaphragm-pneumatics p , arranged 35 in line with said valves and communicating with the tracker-ducts o' . These pneumatics also communicate with the exhaust-chest by the usual small ports p' . The stem j of each exhaust-valve may be provided at its front 40 end with an adjustable head or button q , which bears against the diaphragm of the corresponding pneumatic p .

In the operation of the pneumatic action when the inlet end of a tracker-duct is closed 45 by the traveling music-sheet the air is exhausted therefrom and from the corresponding valve-operating pneumatic p through the small hole p' of the latter, and as the pressure against both sides of the diaphragm is 50 balanced under these conditions the diaphragm is moved by the spring n to the position shown with reference to the two lower diaphragms in Fig. 1. As the corresponding exhaust-valve is now closed and the companion vent-valve open, the corresponding motor-pneumatic D is cut off from the main exhaust-chest E and remains in its normal expanded condition. When a perforation of the 55 music-sheet registers with said tracker-duct, as shown in Fig. 1, the atmosphere enters this duct and the valve-operating pneumatic p and reverses the diaphragm of the latter to the position shown in Fig. 5 and with reference 60 to the upper diaphragm in Fig. 1. The 65 diaphragm in being reversed acts upon the

valve-stem j , opening the exhaust-valve i and closing the vent-valve i' and compressing the spring n , thereby placing the corresponding motor-pneumatic D in communication with the main exhaust-chest and cutting off the 70 outer atmosphere therefrom. This pneumatic being now collapsed by the atmospheric pressure actuates the complementary key of the piano-player. As soon as the corresponding tracker-duct is again closed the motor-pneumatic is allowed to expand, allowing the 75 key to rise to its former position, and the exhaust and vent valves are reversed to their former position by the reaction of the spring n . 80

The valve-adjusting devices permit the position of the exhaust and vent valves of each pair to be nicely regulated by simply screwing the stem j' of the vent-valve a greater or less distance into the valve-rod k , which latter is held against turning in its guides, as hereinbefore described. By making the screw-stem j' adjustable on the valve-rod and in turn making the swiveling vent-valve adjustable on said stem this valve can be approximately adjusted on its stem by means of the 85 nuts m m' before placing the valve in its chamber, and a final accurate adjustment of the same can then be effected by means of the screw-stem, which is accessible from the outer side of said chamber. These adjusting devices are, moreover, simple and inexpensive in construction and can be readily assembled and repaired. 90

In the drawings the motor-pneumatics are represented as being above the main exhaust-chest E ; but they may be located in any other suitable position, their particular construction and arrangement forming no part of my invention. 95

The improvements are herein shown and described in connection with a piano-player as an example of their use. They may obviously be applied to self-playing pianos and similar musical instruments having a pneumatic action. 100

I do not wish to claim in this application the construction of the swiveling exhaust and vent valves herein shown and described, as the same forms the subject of a divisional application filed by me on the 1st day of September, 1904, Serial No. 222,924. 111

I claim as my invention—

1. The combination of an exhaust-chest, a motor-pneumatic, a chamber communicating with said pneumatic and having exhaust and vent ports, a sliding valve-rod carrying an exhaust-valve which controls said exhaust-port, a screw-stem engaging with said valve-rod and accessible from the outer side of said chamber, and a vent-valve controlling said vent-port and capable of longitudinal adjustment on said screw-stem, substantially as set forth. 112

2. The combination of an exhaust-chest, a motor-pneumatic, a chamber communicating 113

with said pneumatic and having exhaust and vent ports, a sliding valve-rod carrying an exhaust-valve which controls said exhaust-port, a screw-stem engaging with said valve-rod and accessible from the outer side of said chamber, a vent-valve controlling said vent-port, and clamping-nuts mounted on said screw-stem and bearing against opposite sides of said vent-valve, substantially as set forth.

10 3. The combination of an exhaust-chest, a motor-pneumatic, a chamber communicating with said pneumatic and having exhaust and vent ports, exhaust and vent valves applied to

said ports, a valve-rod arranged in said valve-chamber and carrying said valves, and a spiral spring surrounding said rod and bearing at one end against said exhaust-valve and at its other end against an abutment in the valve-chamber, substantially as set forth. 15

Witness my hand this 3d day of February, 20
1903.

EUGENE DE KLEIST.
